NILS WILHELM UHR, OF GOTTERNOBORG, AND JOHAN HJALMAR SANDBERG, OF STOCKHOLM, SWEDEN.

SUBFLOATING BODY.

1,179,148.

Specification of Letters Patent. Patented Apr. 11, 1916.

Application filed December 8, 1914. Serial No. 876,079.

To all whom it may concern:

Be it known that we, NILS WILHELM UHR, a citizen of the Kingdom of Sweden, residing at Gottenborg, Sweden, and JOHAN HJALMAR SANDBERG, a citizen of the Kingdom of Sweden, residing at Stockholm, Sweden, have invented new and useful Improvements in Subfloating Bodies, of which the following is a specification.

10 This invention relates to subfloating bodies, as for instance mines, torpedoes or the like, adapted, after having been laid out or launched, to oscillate up and down in the water relatively to a predetermined depth 15 of immersion. The devices hitherto used for effecting such an oscillating movement consist, generally, of a piston, a diaphragm or the like actuated in one direction by a source of power placed in the sub- 20 floating body, and in the other direction by the pressure of the surrounding water, said devices serving to vary the displacement of the subfloating body.

The principal object of this invention is 25 to effect such a variation of the displacement with the smallest possible consumption of energy of said source of power.

Another object of the invention is to provide means for imparting to the subfloating 30 body after having passed the above named predetermined depth of immersion which is hereinafter called central position in one direction, an impulse of movement in the opposite direction, the displacement of the 35 subfloating body then being kept constant or nearly so, until the subfloating body, on account of the said impulse, has changed the direction of movement and moving in the latter direction has passed the said central 40 position, the said body then receiving another impulse of movement in the first named direction, and so on.

With these objects in view the invention 45 consists, chiefly, in this that the pressure of the water on the piston, diaphragm or the like, is substantially balanced by a spring or by means of gas pressure or any other source of power.

These and other objects may be attained

by means of the construction shown in the 50 accompanying drawings, in which:

Figure 1 is a sectional view of a portion of a subfloating body, the source of power of which consists of an electromagnet and a battery. Fig. 2 is a similar sectional view 55 of a portion of a subfloating body provided with a source of power consisting of a spring motor. Fig. 3 is a cross-section through the latter subfloating body, certain details thereof being omitted. Figs. 4 and 60 5 are details of the subfloating body shown in Figs. 2 and 3. Fig. 6 is a sectional view 55 of a subfloating body, the source of power of which consists of a compressed gas receiver.

Referring to Fig. 1, the numeral 1 designates a diaphragm actuated by the pressure of the surrounding water and the outward and inward movement of which increases and decreases respectively the displacement of the subfloating body. The 70 pressure of the water on said diaphragm is, in respect to the central depth of immersion relatively to which the subfloating body shall oscillate up and down, substantially balanced by a spring 2 secured at one 75 end to the shell 2¹ of the subfloating body and connected at the other end with the stem 4 of the diaphragm by means of a lever 3 pivotally mounted on a bolt 3¹. The 80 said lever 3 is in its turn by means of a connecting piece 3¹¹ connected with the armature 5 of an electromagnet 6, said armature being pivotally mounted on a bolt 5¹. The electromagnet is supplied with current from a battery 7, and inserted in the circuit of 85 the electromagnet 6 is a contact device consisting of two contact pins 8 and 9 connected in series and adapted to make contact with two contact springs 10 and 11 90 respectively. The contact springs 10 and 11 are supported by two swingable arms 12 and 13 respectively actuated by a spring 14, which tends to turn the arms 12 and 13 so as to bring the springs 10 and 11 out of 95 contact with the contact pins 8 and 9 respectively. Further, the arms 12 and 13 are by means of two hooks 16 and 17 actuated by a hydrostat, consisting of a diaphragm

15 acted upon by the water pressure and forced outward by means of a spring 15¹¹. The hooks 16 and 17 are pivotally mounted on the stem 15¹ of said hydrostat and actuated by a spring 18 in such manner, that the points of the hooks 16 and 17 bear continuously against the arms 12 and 13 respectively, which, in order to be moved by said hooks, are at the ends facing the hooks 16 and 17 provided with projections 12¹ and 13¹ respectively so located, that the points of the hooks can engage said projections.

The arms 12 and 13 do not only serve to support the contact springs 10 and 11 but 15 form at the same time locking members for the stem 4 of the diaphragm 1. The stem 4 is forked at the inner end thus forming an upper branch 19¹ and a lower branch 19 which latter is hook-shaped at the free end. 20 The arm 12 is at its free end provided with a shoulder 12¹¹ serving to lock the stem 4 in its outermost position, while the arm 13 is provided with a hook or shoulder 13¹¹ adapted to engage the hook-shaped end 19 25 of the stem 4 and thereby to lock the stem in its innermost position.

The device described above operates as follows: When the subfloating body is launched, the diaphragm 1 is kept locked 30 in its innermost position and the body is, therefore, somewhat heavier than the water displaced. The contact between the spring 11 and the pin 9 is broken, while the hydrostat 15 by means of the spring 15¹¹ is kept 35 in its outermost position. The subfloating body descends, and when it passes the central position relatively to which the said body is intended to oscillate up and down, the hydrostat is moved inward by the water 40 pressure. Owing thereto, the point of the hook 16 slides along the arm 12, which bears against the branch 19¹ of the stem 4, while the hook 17 is brought into engagement with the projection 13¹ of the arm 13 and turns 45 the latter upward so that the hook 13¹¹ releases the hook 19, thus allowing the diaphragm 1 to move freely. At the same time as the arm 13 moves upward, its contact spring 11 is brought into contact with the 50 contact pin 9, and since the contact spring 10 is beforehand in contact with the pin 8, the circuit will be closed through the electromagnet 6. Consequently, the electromagnet, being excited, attracts its armature. 55 Fig. 1 shows the subfloating body in this position just before the armature has been attracted, the hydrostat 15 occupying a middle position. The armature, by turning the lever 3, moves the stem 4 and the 60 diaphragm 1 outward, the spring 2 simultaneously facilitating said outward movement. On account thereof, the displacement of the subfloating body is increased, so that the said body becomes lighter than 65 the water displaced by the same. Owing

to its inertia, the subfloating body will, however, continue to move downward some distance, before it commences to move upward. At the same moment as the stem 4 and the diaphragm 1 reach their outer-most 70 positions, the arm 12 slides off the branch 19¹ of the stem 4 so that the shoulder 12¹¹ comes into position behind said branch, because the spring 14 as well as the spring-actuated hook 16 tend to turn the arm 12 75 downward. By the said movement of the arm 12 the contact between the pin 8 and the contact spring 10 is broken, and at the same time the stem 4 and the diaphragm 1 are locked in their outermost positions. 80 Thus the supply of current to the electromagnet 6 will be interrupted, as soon as the electromagnet has performed its operation. By locking the diaphragm 1 in its outermost position the displacement of the subfloating body is kept constant, on the one hand, during its movement to the lower turning position and, on the other hand, during the upward movement, until the said body has passed the central position and the 85 hydrostat 15, on account of the decreasing water pressure, is moved outward by the spring 15¹¹. By this action of the spring 15¹¹ the hook 16 engages the projection 12¹ of the arm 12 and swings said arm upward 90 thereby interrupting the engagement between the shoulder 12¹¹ and the inner end of the branch 19¹ of the stem 4 and at the same time restoring the contact between the contact pin 8 and the contact spring 10. The 100 circuit will not, however, be closed, since the spring 14 turns the arm 13 now released from the hook 17 downward, so that the contact between the contact pin 9 and the contact spring 11 is broken. The lower surface of the hook 13¹¹ bears now against the upper surface of the hook 19, and as soon as the water pressure on the diaphragm 1 slightly exceeding the tension of the spring 2 moves the diaphragm 1 to its innermost 110 position, the hook 13¹¹ will by the action of the spring 14 catch the hook 19, thereby locking the stem 4 and the diaphragm 1 in their innermost positions. Owing to the 115 inward movement of the diaphragm 1, the subfloating body will again be heavier than the water displaced by the same. On account of its inertia the said body will, however, move some distance upward before turning. In the downward movement of 120 the body the diaphragm 1 will be kept locked in its innermost position, until the body passes the central position, whereupon the play described above will be repeated.

In the form of the invention shown in 125 Figs. 2 to 5 a spring 2 is as in Fig. 1 used for compensating the greater part of the water pressure on the diaphragm 1 when the subfloating body is in its central position in the water. In this case the source of 130

power effecting the outward movement of the diaphragm 1 consists of a spring motor 20, the shaft 21 of which by means of a driving gear 22, 23, 24, 25, 26 and 27 (see Fig. 4) actuates, on the one hand, a star-wheel 28 serving to move the stem 4 of the diaphragm 1 and, on the other hand, a member 29. The said driving gear comprises a ratchet wheel 22 rigidly secured to the shaft 21 of the motor 20, a spring-actuated pawl 23 engaging said ratchet wheel 22 and placed on a spur-wheel 24, which is loosely mounted on the shaft 21 and engages a spur-wheel 25 secured to a shaft 25¹. Secured to the shaft 25¹ is another spur-wheel 26 in engagement with a spur-wheel 27 mounted on a shaft 27¹. The star-wheel 28 is secured to the shaft 25¹ and the member 29 to the shaft 27¹. By the arrangement of the ratchet wheel 22 and the pawl 23 the spring-motor can be wound up in the usual manner. The stem 15¹ supports, just as is the case in the form of the invention shown in Fig. 1, two hooks 16 and 17 coacting with arms 12 and 13 respectively for locking the stem 4 of the diaphragm 1 in its outermost and innermost position respectively. The arm 12 is arranged in the same manner as in Fig. 1, while the arm 13 does not only serve to lock the stem 4 of the diaphragm 1 in its innermost position but constitutes also together with the member 29 a stopping device for the spring motor 20.

The construction and the mutual arrangement of the members 13 and 29 are shown in Fig. 5. The member 29 which is secured to the shaft 27¹ is at its free end provided with two projections 30 and 31 placed diagonally on the end surface of said member, while the arm 13 is provided on the one hand with a hook 32 serving to lock the stem 4 in its innermost position and on the other hand with a lateral projection 33 adapted to stop the member 29. When the member 29 occupies a position at right angles to the arm 13 as shown at the left side of Fig. 5, the lateral projection 33 can pass between the projections 30 and 31, thereby permitting the arm 13 to swing downward.

The device shown in Figs. 2 to 5 operates as follows: In laying out or launching the subfloating body, the diaphragm is in its innermost position, the stem 4 being locked by the hook 32 of the arm 13 engaging the corresponding hook-shaped projection 19 of the stem 4, while the hydrostat 15 is kept in its outermost position by the spring 15¹. The spring motor 20 is stopped on account of the members 13 and 29 occupying the positions shown at the left side of Fig. 5. When the subfloating body in the downward movement has passed the central position, the hydrostat 15 is moved inwardly, and, owing thereto, the hook 17 turns the arm 13 downwardly thereby releasing the

stem 4, while the lateral projection 33 passes downwardly between the projections 30 and 31 of the member 29. As soon as the projection 30 has been disengaged from the lateral projection 33, the member 29 by the action of the spring motor 20 makes one revolution and is then stopped by the arm 13 in the position shown at the right side of Fig. 5. While turning the member 29 one revolution, the spring motor at the same time turns the star wheel 28 which engaging a tooth 4¹ on the stem 4 moves the diaphragm 1 to its outermost position.

In this position of the diaphragm the arm 12 engages the inner end surface of the stem 4, thus locking said stem in its outermost position. The subfloating body has now received an impulse for the upward movement, and the spring motor as well as the diaphragm 1 have then been stopped and made inoperative. The subfloating body continues, however, to move downward some distance before returning upward. When passing the central position in the upward movement, the hydrostat 15 is moved outward, and, on account thereof, the hook 16 turns the arm 12 upward thereby releasing the stem 4, while the hook 17 is disengaged from the arm 13, which in its turned down position (at the right side of Fig. 5) keeps the spring motor stopped. When the diaphragm 1 moves inward, owing to the water pressure, the arm 13 is turned upward, so that the hook 32 of the said arm 13 engages the hook 19 of the stem 4, thereby locking said stem in its innermost position. By this movement of the arm 13 the stopping member 29 will be released and turned to the position shown at the left side of Fig. 5. The subfloating body has now received an impulse for downward movement, but continues to move upward before turning downwardly. When passing the central position, the hydrostat 15 is actuated by the water pressure, and the play described above is reiterated.

In the form of the invention shown in Fig. 6 the counteracting of the water pressure on the diaphragm 1 is effected by means of compressed air or other gas contained in a closed compartment 34. In this case a piston 35 is substituted for the stem of the said diaphragm, said piston being actuated by compressed air or other gas contained in a receiver 36. The hooks 16 and 17 supported by the stem 15¹ of the hydrostat 15 serve to control the supply of compressed gas to the cylinder 35¹ of the piston 35 by the aid of spring actuated valves 37 and 38, the stems 37¹ and 38¹ respectively of which are pivotally connected with the arms 12 and 13 respectively actuated by the hooks 16 and 17 respectively.

The device shown in Fig. 6 operates as follows: At the outset the diaphragm 1 occu-

pies its outermost position, under the action of the gas pressure in the compartment 34 and likewise the hydrostat 15 is kept in its outermost position by the spring 15¹¹. In this position the valve 37 is open and the valve 38 closed. When launched the sub-floating body is, accordingly, somewhat lighter than the water displaced, but by reason of the fact that it is launched from a point over the water surface it receives a sufficient momentum for sinking to such a depth that the outer water pressure moves the diaphragm 1 to its innermost position. When the subfloating body then in its downward movement passes the central position and the hydrostat 15 is pressed inward by the water pressure, the hook 16 releases the arm 12, so that the valve 37 is pressed against its seat by the spring 37¹¹. The hook 17, on the contrary, turns the arm 13 upward so as to open the valve 38, so that compressed gas from the receiver 36 entering the cylinder 35¹ can move the piston 35 together with the diaphragm 1 outward. On account thereof the displacement of the subfloating body is again increased, so that said body becomes lighter than the water displaced. Owing to its inertia the subfloating body continues, however, to move some distance downwardly before returning. When the subfloating body passes its central position, the hydrostat is pressed outward by the spring 15¹¹, the hook 17 thereby releasing the arm 13, so that the spring 38¹¹ will be allowed to close the valve 38. At the same time or a moment after the arm 12 is actuated by the hook 16 in such manner that it opens the valve 37. The compressed gas contained in the cylinder 35¹ now escapes, so that the water pressure can move the diaphragm 1 and the piston 35 inward, thereby rendering the subfloating body heavier than the water displaced. Fig. 6 shows the subfloating body in this position. When the subfloating body, owing to its inertia, has moved upward some distance and then returning downward passes the central position, the play described above is reiterated. On account of the counteracting of the water pressure by means of the gas pressure in the compartment 34, the pressure in the receiver 36 may be kept relatively low or, if a high pressure is used, the piston area may be taken small and the consumption of gas thereby be reduced.

Having now described our invention, what we claim as new and desire to secure by Letters Patent is:

1. In a subfloating body adapted to perform an oscillating movement about a position of equilibrium below the surface of the water, the combination of means for varying the displacement of the body, a source of power for effecting the variations of displacement, a hydrostatic device controlling

said source of power, and means for constantly counteracting the water pressure on the displacement varying means.

2. In a subfloating body adapted to perform an oscillating movement about a position of equilibrium below the surface of the water, the combination of a yielding member for varying the displacement of the body, a source of power for effecting the variations of the displacement, a hydrostatic device controlling said source of power, and means for constantly counteracting the water pressure on the said yielding member. 70

3. In a subfloating body adapted to perform an oscillating movement about a position of equilibrium below the surface of the water, the combination of a yielding member adapted to be actuated upon in one direction by the pressure of the surrounding water when the body has been launched, a source of power for periodically acting upon said yielding member in the other direction, a hydrostatic device controlling said source of power, and means for constantly counteracting the water pressure on said yielding member. 80

4. In a subfloating body adapted to perform an oscillating movement about a position of equilibrium below the surface of the water, the combination of a yielding member for varying the displacement of the body, means for locking said member in its innermost and outermost positions, a source of power for effecting the variations of the displacement, a hydrostatic device controlling said source of power, and means for constantly counteracting the water pressure on said yielding member. 95

5. In a subfloating body adapted to perform an oscillating movement about a position of equilibrium below the surface of the water, the combination of a yielding member for varying the displacement of the body, means for locking said member in its innermost and outermost positions, a source of power for effecting the variations of the displacements, a hydrostatic device controlling said locking means and said source of power, and means for constantly counteracting the water pressure on said yielding member. 100

6. In a subfloating body adapted to perform an oscillating movement about a position of equilibrium below the surface of the water, the combination of a yielding member adapted to be actuated upon in one direction by the pressure of the surrounding water when the body has been launched, a spring constantly counteracting the pressure of the water on said yielding member, a source of power for periodically acting upon said member, and a hydrostatic device controlling the operation of said source of power. 110

7. In a subfloating body adapted to perform an oscillating movement about a position of equilibrium below the surface of the water, the combination of a yielding member adapted to be actuated upon by the pressure of the surrounding water, when the body has been launched, a spring for constantly counteracting the pressure of the water on said yielding member, a spring motor for periodically acting upon said member, means for locking the yielding member in its innermost and outermost positions, and a hydrostatic device controlling said locking means and said spring motor.

In testimony that we claim the foregoing 15 as our invention, we have signed our names in presence of two subscribing witnesses.
